UNITED STATES PATENT OFFICE.

ISAAC Q. GURNEE, OF BUTLER, AND ALBERT A. SMITH, OF RIVERDALE, NEW JERSEY,
ASSIGNORS TO SUPERIOR HARD RUBBER COMPANY, OF BUTLER, NEW JERSEY, A
CORPORATION OF NEW JERSEY.

DESIGN FOR A THERMOMETER CASE.

Application filed February 15, 1927. Serial No. 20,777. Term of patent 14 years.

To all whom it may concern:

Be it known that we, ISAAC Q. GURNEE and ALBERT A. SMITH, citizens of the United States, residing at Butler, in the county of Morris and State of New Jersey, and Riverdale in the county of Morris and State of New Jersey, respectively, have invented a new, original, and ornamental Design for Thermometer Cases, of which the following is a specification, reference being had to the accompanying drawings, forming part thereof.

Figure 1 is a side view of our new design; Figure 2 is an opposite side view; Figure 3 is a top view; and Figure 4 is a bottom view of same.

We claim:

The ornamental design for a thermometer case; as shown.

Signed at Butler, in the county of Morris and State of New Jersey, this 24th day of December, 1926.

ISAAC Q. GURNEE.
ALBERT A. SMITH.
